COMBINATION LOCK

Julien Henri Porché, Paris, France

Application August 1, 1947, Serial No. 765,517
In France January 24, 1939Section 1, Public Law 690, August 8, 1946
Patent expires January 24, 1959

11 Claims. (Cl. 70—153)

1

The present invention relates to so-called combination or puzzle-locks of the type which is operated by means of one single control member, which needs no key for locking and unlocking the device, and combined with an arrangement for automatically locking a door as soon as the same is closed.

This type of mechanism is known in its application to containers designed to contain articles which it is desired to keep safe from thieves. In particular, devices of this kind were used for locking chests, wardrobes or boxes of all stationary or portable types, and even, in a purposely simplified form, on cars which it is often desirable to lock rapidly and carefully when they contain possibly valuable items such as commercial travellers' samples or goods, tourists' luggage, etc.

One object of this invention is to provide an inviolable lock intricate in its combinations but which can be operated simply and rapidly, which also enables the operator to lock doors automatically at their closing, which is simple in its construction and whose outer members will not interfere with the lock of the door. In addition, where applied to an automobile body, the lock must be capable of adaptation to existing door-locks.

Another object of the invention is to provide a lock of the character hereinabove indicated, whereby the engagement or release of the lock is effected by operating one simple control member first in one direction and then in the other direction in predetermined increments.

A further object of the invention is to provide a lock as defined in the last preceding paragraph, and wherein displacement of the control member on its axis, combined with rotary movement thereof, is necessary to release the lock.

A further object of the invention is to provide a lock of the combination type wherein simple arrangements are provided to change the operating combination.

A further object of the invention is to provide a lock of the character described wherein the control member is also adapted to perform some of the functions heretofore served by parts of the conventional door lock.

In the diagrammatic drawings:

Figure 1 is a front view showing the essential mechanism of the lock in the open position;

Figure 2 is a fragmentary cross-sectional view of the lock in the coupled position, taken on line A—A in Fig. 1;

Figure 3 is a front view of the movable stop 55 as cams 7 and 8.

2

system in its "zero" position, the lock being in its open position;

Fig. 4 is a view similar to Fig. 3 but showing the parts in a different operating position.

5 Figure 5 is a general cross-sectional view of a three digit combination lock;

Figures 6 and 7 show the details of operation of said lock.

10 While the lock now to be described is capable of adaptation to closures of a variety of types, it will be described herein as applied to an automobile door, merely by way of an example.

15 The lock according to the embodiment described comprises essentially (Figs. 1 and 2) a pair of idle wheels 1, 2 carrying pawls 3, 4 by which ratchet-wheels 5, 6 rigidly secured to cam-wheels 7, 8 are driven in opposite directions relative to one another.

20 The cams co-operate with studs 9, 10 integral with a sliding plate 11 the end 12 of which comes into engagement with a member 13 operable to block a door-lock (e. g. that of an automobile) of usual design (not shown).

25 On the other hand, pins 14, 15 secured on a supporting plate 16 allow the above mentioned sets of cams, ratchets and wheels to rotate freely.

Carried at one end of pins 15, 14 are hand levers 17, 18 movable about said pins, and carrying retractable stops 23 spring biased to advanced position.

30 The cam-wheels 7, 8 form discs provided on one face thereof with a plurality of recesses 19 intended to produce the clicking noise when the lock is being operated and with holes 20 for the passage of the retractable stops, said holes being in registry with the recesses or cams proper 9a, 10a, of the cam-wheels 7 and 8.

Moreover, the supporting plate is drilled with a plurality of holes 21 providing passages for balls 40 22 swaged in movable stops 23 pressed upon the plate 16 by means of springs 24 and guided by stems 25 carrying hold-knobs 26, the whole being housed in movable hand-levers 17, 18 and the units thus composed providing what may be 45 called retractable movable stops.

The rotation of wheels 1, 2 is controlled by a central wheel 27 carrying pins 28 and which can rotate freely on a fixed bushing 29 acting as a pivot axis and receiving a central shaft 30 provided at one end thereof with a control-knob 31 rigid therewith.

Moreover, secured on the central shaft 30 is a disc 32 formed with holes 33 spaced in correspondence with recesses 19 and holes 20 as well

The central shaft 30 which carries control knob 31 can be axially displaced by turning knob 35 of screw 34 so as to move shaft 30 to the right (Fig. 2) against the bias of spring 31. Such displacement disengages a clutch comprising disk 32 on the shaft and pins 28 on gear 27, so that when the clutch is disengaged rotation of the knob has no effect on the cam wheels, the knob merely rotating on the end thrust ball 36. The screw 34 operates in complementary threads in a fixed bushing 29, which also supports the fixed end of a spring 39 effective on plate 11.

The operation of the lock will now be described. From a glance at Figs. 3 and 4, in conjunction with a knowledge of the latch bolt operation of the conventional door lock, it will be apparent that detent 13 must have its finger tip detached from the cooperating bolt actuating means before said detent means can be operated to release the actuating means. In other words, viewing the dotted line showing at the top of Figs. 3 and 4, the lever 13 must be moved from the Fig. 4 position to the Fig. 3 position. For this purpose sliding plate 11 must be caused to move upwardly to contact with the rear end of lever 13 to disengage it. Plate 11 is normally biased by spring 39 to such upper position, but is prevented from moving to such upper position by the fact that cam following pins 9 and 10, integral with plate 11, are normally riding on the raised periphery of the cam portions of cam wheels 7 and 8. Upward movement of plate 11 is permitted only when said cam wheels 7 and 8 are rotated to such registered position that recesses 9a and 10a are simultaneously in registry with pins 9 and 10 respectively, so that the said pins can snap into said recesses under the bias of spring 39, thereby permitting sliding plate 11 to move.

By means of the operation of knob 31, shaft 30, gear 27, and idler wheels 1 and 2, and the intermediate pawls 3 and 4, cam wheels 7 and 8 may be moved in succession to any desired detent stop, but the operator must know when to stop rotation of knob 31 in one direction after registering pin 9 with recess 9a for example, and when to begin rotation of knob 31 in the other direction so as to register pin 10 with recess 10a. The operator must therefore first establish a zero position, and then rotate the several cam wheels a known number of clicks, first in one direction, and then in the other direction.

A zero positioning is established by registry of the ball tips of retractable stops 23 with the holes 20 in the cam wheels 7 and 8. On rotation of each cam wheel by means of knob 31, the ball tip clicks over depressions 19 in sequence until a materially increased resistance is encountered when the ball tip drops into hole 20. Rotation of knob 31 is then reversed in direction until the corresponding registry is obtained with the other cam wheel. The zero point is thus established for each cam wheel.

After establishment of the zero point the operator must be familiar with the angular displacement, measured in number of clicks, which must be accomplished by movement of each cam wheel away from said zero point, in order to bring each recess 9a or 10a into registry with its respective pin 9 or 10.

Such angular displacement is controlled by presetting of the movable arms 17 and 18 which carry the retractable stops. For each cam wheel the retractable stop can be drawn back, and the

arm thereafter preset in any one of the ten positions indicated. This determines the number of clicks through which the cam wheel must be turned in order to bring recess 9a, for example beneath pin 9, and when the corresponding operation is performed for the other cam wheel, plate 11 will operate as heretofore described.

In rotating the presetting arm 18 for example, knob 26 is pulled out against the bias of spring 10 24 until ball tip 22 clears supporting plate 16, after which the arm 18 may be rotated to any desired position.

To set a lock for the combination 7-6 for example (as shown in Fig. 4) arm 17 is moved to 15 place its retractable stop in position numbered 7, and arm 18 is similarly moved to place its retractable stop in position numbered 6. Starting from the zero point for each cam wheel, 20 movement of the upper cam wheel seven clicks counterclockwise and movement of the lower cam wheel six clicks clockwise results in arrival of recess 9a under pin 9 and recess 10a under pin 10 as hereinbefore described, whereupon lever 11 is permitted to move upwardly.

25 In the embodiment of the invention shown in Figs. 1 to 4, once the combination has been properly operated, and the sliding plate 11 has moved to the position shown in Fig. 1, the dog may be operated freely by the normal door handle as many times as desired provided knob 31 is not rotated to disturb the position of either cam wheel 7 or 8. Once such position has been disturbed, then the combination must be again operated to permit operation of the dog.

35 A possible embodiment of a lock according to this invention, designed to operate on a three digit combination, is shown in cross-sectional view in Fig. 5. The figure also shows, together with Figs. 6 and 7 how said lock is connected with a door-latch of any conventional known type.

The constructional structure of the lock according to this example is similar to that of Figs. 1 to 4 and its operation is also similar when 45 knob 31 is rotated in one direction or the other. The third digit combination figure comes here into play when the knob 31 is pulled to the right or pushed to the left.

For that purpose, the stem 30' of knob 31 50 carries a disc 51 formed with a groove 52 co-operating with a lever 54 rockable about a stationary pin 55. The other end of said lever is formed with a fork 57 straddling a pin 58 carried by a slider comprising a supporting stem 59 and a plurality of rollers 60, 63, 64, 65, 66, 55 said member being guided in a sleeve 69 mounted in the supporting plate 16'. The said slider projects through an aperture 68 in the locking plate 11'. One of the rolls 63-66, for instance roll 63, 60 has a smaller diameter than the others, so that when same is engaged in the aperture 68 in plate 11' the latter is not prevented from moving upwards for a certain distance, whereas in the position shown in Fig. 5 a displacement of the plate 11' in the upward direction is impossible.

Moreover, the stem 30' is formed with slots or 65 grooves 45, 46, 47, 48, 49 co-operating with a ball-stop 43. When the knob 31 is pulled the ball will skip from one groove into the next thus marking positions of rest in the axial shifting of knob 31 corresponding to the positions of rolls 63-66 with respect to plate 11'. Thus, when the knob is pulled by three notches with respect to 70 75 the position of the stop in Figure 5, the smaller

roll 63 will register with the aperture 68 in plate 11' and thus unlock the latter which thenceforth can move upwardly when urged to do so. A figure "3" can thus be set.

By altering the position of roll 63 with respect to the others a similar alteration is obtained in this figure of the combination.

As already pointed out, the lock can be associated, such as described above, with any desired latching or bolting device, particularly with the doors of now existing automobiles, it being only necessary to fit a small number of intermediate members between the lock according to this invention and one of any conventional type which at the same time will permit to obtain a now automatic latching, as will be hereinafter described.

The bolt 101 of a lock, e. g. that of known automobile doors, is fitted with an abutment or stud 78 (Fig. 6). For retracting said bolt, that is, for opening the vehicle, the handle of the latter, integral with a shaft 90, is actuated, a member provided with a finger 91 being secured on said shaft. The said finger 91 acts on a stop 78 and urges the bolt 101 to the left.

The arrangement described has been taken advantage of by complementing the same with a lug 103 facing in the direction shown in Fig. 6 and designed to co-operate with a multi-armed bell crank lever 102 pivotally mounted on a pin 104.

Mounted on the same pin 104 is catch 13 which registers with one similarly catch-shaped arm 93 of said lever 102. Both catches are in engagement with lug 103. Lever 102 comprises a finger 79 located on the path of stud 78 and a finger 81 in engagement with a catch lever 84 rockable about a pin 105 and maintained in the position shown in Fig. 6 by a spring 87.

As the gear wheel 27 of the combination lock as previously described and fitted on the plate 16' is turned in a counterclockwise direction, Fig. 6, to bring the recess 9a of the upper cam wheel 7 into registry with the stud 9 of the sliding plate 11', an abutment stud 89 on said gear wheel 27 is brought into engagement with a projection 88 on a catch lever 84. Upon continued rotary movement of the gear wheel 27, the abutment stud 89 thereof moves said catch lever 84 to the left, Fig. 6, with the consequent release of the upper end of said catch lever from its retaining engagement with the finger 81 of the multi-armed lever 102 and the further consequent release of the catch arm 93 of such lever from its retaining engagement with the lug 103. As a result, when the member 13 is released from its retention of the lug 103 by the elevation of the sliding plate 11', the opening of the door can be effected by operation of the door handle (not shown) which is operatively connected with the shaft 90, the door handle being actuated to cause the finger 91 to move to the left or counterclockwise, Fig. 6, to thereby effect retracting movement of the latch bolt 101 with respect to its cooperating keeper (not shown).

However, the pressure on the door handle being continued, stud 78 throws the arm 79 back into its position shown in Fig. 6, against the bias of spring 95. The finger 81, snaps past catch lever 84, catch 93 comes again into the position shown in Fig. 6 and as soon as the door handle rigid with shaft 90 is released the finger 91 is set again into engagement as shown in Fig. 6 through the medium of lug 103 rigidly secured therewith. Catch 93 and lug 103 have only a very small por-

tion of their surfaces in mutual engagement in Fig. 6. One or both (catch 93 and lug 103) have an inclined camming side surface on the side adjacent the mutually engaging portions, and one or both are somewhat loosely mounted on plate 16. Then, when the spring inside the latch bolt 101 drives it toward the locked position, stud 78 in moving to the right in Fig. 6 rotates finger 91 clockwise and forces the camming side surface or surfaces to move catch 93 and lug 103 sidewise out of interfering alignment. When they reach the position in Fig. 6, the catch 93 and lug 103 return to normal unstrained position so that the door handle is blocked from rotating counterclockwise.

If the door is now slammed, the bolt 101 interlocks with the keeper, but since the door handle is blocked, the door is bolted. In order that the catch 84 can be kept away from its position according to Fig. 6, that is, for the purpose of cancelling the effect of automatic locking, an arrangement as shown in Fig. 7 is provided which consists of a knob 74 which is screw-threadedly engaging a nut 70 and which carries an intermediate member 72 provided with a bevel-shaped peg 76. When the plate 11' has returned upwards to its position of unlocking and when the knob 74 is screwed, the said peg is able to come into engagement with a notch 100 in plate 11' and at the same time with a projection on catch-lever 84 so as to move the latter away from the locked position shown in Fig. 6. Positioning of peg 76 in notch 100 maintains plate 11' in its upward or door unlocking position, and engagement of peg 76 with catch lever 84 keeps the tip of said catch lever permanently out of engagement with crank lever arm 81. The combination knob cannot be operated because pins 9 and 10 are permanently held in recesses 9a and 10a but disengagement of both levers 13 and 102 from member 91 permits the door handle to be manipulated as often as desired in conventional manner. The automatic actuation of the lock is thus cancelled and the door operates normally. It follows that the opening and closing of the door are completely free, which enables the user to keep his combination secret.

It is to be understood that the embodiments described above by way of example, though deemed to be advantageous, are by no means of limitative character, since the locks according to this invention, as well as the automatic members, can be designed differently depending on the conditions of use particularly on which locks of conventional pattern they are to be associated with.

I claim:

1. In a lock structure having a bolt member movable to and from locking position and actuating means for moving said bolt member from locking position and detent means engageable with said actuating means to prevent it from moving said bolt member from locking position, control mechanism for the release of said detent means, said control mechanism comprising a support, a slide bar movably mounted on said support and having a pair of longitudinally spaced cam followers, means normally urging said slide bar to a position to release said detent means from engagement with said actuating means, means on said support preventing such movement of said slide bar, comprising a pair of cam wheels on said support cooperable with said cam followers and having low points which when in simultaneous engagement with said cam followers per-

mit movement of said slide bar to detent means releasing position, means for the independent rotation of said cam wheels, and means for determining when each of said cam wheels has been rotated to an extent to bring its low point into engagement with a cam follower of the slide bar.

2. Mechanism as defined in claim 1, wherein the cam wheels are independently rotatable by a single means, rotatable in one direction to effect rotary movement of one cam wheel and rotatable in the opposite direction to effect rotary movement of the other cam wheel.

3. Mechanism as defined in claim 1, wherein means is provided for disengaging said cam wheel rotating means from said cam wheels whereby to prevent operation of said cam wheels by said rotating means during such disengagement.

4. Mechanism as defined in claim 1, wherein the means for indicating the position of the low point of each cam wheel with respect to a cam follower comprises an adjustably fixed spring impelled plunger carried by said support in contact with the face of the cam wheel, said face being provided with a spaced series of depressions in the path of contact of said plunger when said cam wheel is rotated, whereby said plunger clicks successively into each depression during cam wheel rotation, one of said depressions in said path being deeper than the others whereby to increase the resistance of cam wheel rotation as the plunger encounters said deeper depression, and thereby provide a point of reference in determining a starting point for cam rotation.

5. Mechanism as defined in claim 1, wherein additional control mechanism is provided for said slide bar, such mechanism including a plurality of elements successively engageable with said slide bar, one of said elements having a low point which when in registry with said slide bar permits said slide bar to be moved into detent means release position.

6. Mechanism as defined in claim 1, wherein additional control mechanism is provided for said slide bar, such mechanism including a plurality of elements successively engageable with said slide bar, one of said elements having a low point which when in registry with said slide bar permits said slide bar to be moved into detent means release position, the position of the element having such low point with respect to the other elements being variable as desired.

7. Mechanism as defined in claim 1, wherein additional control mechanism is provided for said slide bar, such mechanism including a plurality of elements successively engageable with said slide bar, one of said elements having a low point which when in registry with said slide bar permits said slide bar to be moved into detent means release position, and wherein the movement of such elements is under the control of the means for rotating the cam wheels.

10 8. Mechanism as provided in claim 1, wherein holding means is provided for cooperation with said actuating means to prevent it from moving the bolt member from locking position when the slide bar is in detent releasing position.

15 9. Mechanism as provided in claim 1, wherein holding means is provided for cooperation with said actuating means to prevent it from moving the bolt member from locking position when the slide bar is in detent releasing position, and wherein means is provided for the release of said holding means.

20 10. Mechanism as provided in claim 1, wherein holding means is provided for cooperation with said actuating means to prevent it from moving the bolt member from locking position when the slide bar is in detent releasing position, said holding means being under the control of the means for rotating the cam wheels.

25 11. Mechanism as provided in claim 1, wherein holding means is provided for cooperation with said actuating means to prevent it from moving the bolt member from locking position when the slide bar is in detent releasing position, and wherein means is provided for rendering said holding means ineffective when desired.
